UNITED STATES PATENT OFFICE

GEORGE F. GREEN, OF EAST PROVIDENCE, RHODE ISLAND

JEWELRY-DISPLAY DEVICE

Application filed December 5, 1929. Serial No. 411,824.

My present invention relates to jewelry display devices, and has particular reference to boxes for displaying rings and the like.

One object of the invention is to simplify the construction of this type of display device.

Another object is to reduce the number of steps necessary for assembling the display device.

10 A further object is to reduce the cost of manufacture of a device of this character.

With these and other objects and advantageous features in view, the invention consists in a novel method of assembly and a 15 novel arrangement of parts more fully disclosed in the detailed description following, in conjunction with the accompanying drawings, and more particularly set forth in the appended claims.

20 In the drawings:

Fig. 1 is a perspective view of an assembled display box;

Fig. 2 is a central section thereof;

25 Fig. 3 is a perspective view of one of the jewelry gripping elements;

Fig. 4 is a perspective view of the fabric-coated cardboard used for blanking out the jewelry gripping elements;

30 Fig. 5 is a plan view of an element blank;

Fig. 6 is a sectional view showing the gripping of a ring; and

Fig. 7 is a section on the line 7—7 of Fig. 6.

It has been found desirable to simplify the construction and the assembly of jewelry

35 display devices. I have devised a jewelry device which includes hollow gripping elements assembled from fabric-covered, resilient

cardboard blanks, the front wall of each element being arcuate, and positioned in op-

40 posed relation to the front wall of a similar element to yieldingly receive an article of jewelry therebetween. I have also utilized the rear walls of the elements as resilient

members continually urging the front walls

45 forwardly, and I have found that the side walls of the hollow elements, when assem-

bled in a container, serve to maintain the front walls against crushing; and the follow-

50 ing is a detailed description of a preferred constructional embodiment of my invention.

Referring to the drawings, the specific novel display device illustrated includes a container 10, preferably rectangular, with two hollow elements 11 positioned therein in opposed relation. Each hollow element, as shown in 55 Fig. 3, has a rear wall 12, side walls 13, and a front wall 14, the upper portion of the front wall being arcuate and extending over to and joining the rear wall, and the upper portions of the side walls also being arcuate to 60 fit under the edges of the front wall.

As shown in Fig. 3, the rear wall extends rearwardly, and acts as a spring member for forcing the front wall outwardly, when the hollow elements are inserted into a container, 65 thus closing the gap between the opposed front walls.

The hollow element 11 is preferably folded from a blank 15, shown in Fig. 5, which is stamped or cut from a sheet 16 formed of a 70 cardboard base 17 and a covering of fabric or the like 18 secured thereto by any suitable means, such as glue or the like. The blank 15, when stamped out, is also creased as indicated at 19, 20, 21 and 22, Fig. 5, and the 75 parts are then folded as shown in Fig. 3. In certain cases, a filling of cotton or similar yielding material may be inserted in the elements, the walls then being secured together; but I find that the hollow element will function perfectly for all ordinary usage, and that no glue or other securing means for the 80 walls is necessary.

When two hollow elements are assembled into a container, as shown in Figs. 1 and 2, 85 the rear walls push the front walls into contact to hold the elements in the container, and to present a pleasing appearance; when a ring such as shown in Fig. 6 is inserted, the front walls move back against the yielding resistance of the rear walls until the side walls 13 contact with the rear wall or the container walls, and then resiliently yield in the center to accommodate the ring, as shown in Fig. 7. 90 The container walls are preferably resilient 95 to accommodate this yielding, particularly when the article of jewelry is relatively thick.

The resilience of the rear and front walls therefore causes the article of jewelry to be 100

firmly gripped therebetween, irrespective of the length of nap of the fabric covering. This construction therefore eliminates need for a covering having a long warp; the elements may, if desired, be of cardboard alone, but a fabric covering is preferred to avoid scratching.

While I have described a preferred embodiment of my invention, changes in the form and in the assembly of the display may 10 obviously be made, without departing from the spirit and the scope of the invention as defined in the appended claims.

I claim:

15 1. A box for displaying jewelry, said box being provided with two opposing members, one of said members including means to resiliently engage an article to be held between it and the other member, said means being anchored along a substantially vertical line on each side of the article so held and being formed from flat sheet material independent of the box structure.

20 2. A box for displaying jewelry, said box being provided with two opposing members, both of said members including means to resiliently engage an article to be held between it and the other member, said means being anchored along a substantially vertical line 25 on each side of the article so held and being formed from flat sheet material independent of the box structure.

30 3. A box for displaying jewelry, said box being provided with two opposing members, one of said members including a front wall 35 to resiliently engage an article to be held between it and the other member, said front wall being anchored along a substantially vertical line on each side of the article so held and being formed from flat sheet material 40 independent of the box structure.

35 4. A box for displaying jewelry, said box being provided with two opposing members each having a front wall to resiliently engage 45 an article to be held between it and the other member, and side walls for anchoring the front walls along substantially vertical lines on each side of the article so held, the front and side walls being formed from flat sheet material 50 independent of the box structure.

55 5. A box for displaying jewelry, said box being provided with two opposing members each having a front wall to resiliently engage an article to be held between it and the other member, and side walls integral with the front walls for anchoring the front walls along substantially vertical lines on each side of the article so held, the front and side walls 60 being formed from flat sheet material independent of the box structure.

In testimony whereof I affix my signature.
GEORGE F. GREEN.
